UNITED STATES PATENT OFFICE.

WILLIAM J. REGAN AND WILLIAM KELSO, OF PITTSBURGH, PENNSYLVANIA, ASSIGNEES TO THE MC CONWAY & TORLEY COMPANY, OF PITTSBURGH, PENNSYLVANIA, A CORPORATION OF PENNSYLVANIA.

CAR COUPLER.

Application filed May 28, 1927. Serial No. 194,984.

This invention relates to car couplers of the vertical plane type in which outward rotation of the pivoted knuckle is normally prevented by a gravity actuated locking block.

The primary object of the invention is to provide a car coupler formed of strong, simple and reliably operating parts in which the movement of the lock to lock-set position is positively effected, wherein an ample throw of the knuckle opening lever is produced in a coupler of restricted vertical dimensions, and in which the coupler lock affords a large bearing area for the tail of the rotatable knuckle.

A principal feature of the invention consists in providing means whereby the lock for the knuckle upon coming into engagement with the knuckle opener lever is positively tilted so as to assume a position permitting it to be supported in unlocked position on the tail of the knuckle while the latter is closed.

Another feature of the invention, generally stated, consists in providing the knuckle opener lever and the lock for the knuckle with cooperating parts whereby the lock is tilted from its normal position in the act of operating the knuckle opener.

A further feature of the invention consists in forming the locking block on the side adjacent the knuckle with a recess or indentation for receiving the shorter arm of the knuckle opening lever when the lock performs an extended unlocking movement.

Other features of the invention, relating to advantageous forms and combinations of parts, will hereinafter appear and be pointed out in the claims.

In the drawings,—

Figure 1 is a plan view of a preferred embodiment of the invention, a portion of the coupler head being broken away to disclose the interior mechanism.

Figure 2 is a view, partly in side elevation and partly in vertical section, of the coupler, the parts being shown in normal locked relation and assembled for use with a release rigging arranged beneath the coupler.

Figure 3 is a front elevational view of the coupler, the parts being in locked relation.

Figure 4 is a detail view, partly in elevation and partly in vertical section, showing the parts in normal locked relation.

Figure 5 is a detail view corresponding to Fig. 4 but illustrating the relation of the lifter to the lock after the lifter has performed its initial unlocking movement.

Figure 6 is a detail view, partly in section and partly in elevation, showing the locking block raised sufficiently to permit it to tilt so as to be supported in lock-set position on the tail of the knuckle.

Figure 7 is a view corresponding to Fig. 6 but showing the locking block tilted so as to position its lock-set leg over the lock-set seat of the knuckle.

Figure 8 is a detail view, partly in section and partly in elevation, showing the locking block raised to its extreme height to effect an uncoupling rotation of the knuckle.

Figure 9 is a detail view, partly in elevation and partly in vertical section, illustrating the relation of the locking block and knuckle opener when these parts first come in contact.

Figure 10 is a perspective view of the locking block.

In the drawings, 1 is the coupler head, 2 is the knuckle, and 3 is the knuckle pin by which the knuckle is rotatably mounted upon the coupler head in a well known manner. In the form of the device illustrated in the drawings, the stem or shank 4, which forms a part of the coupler body, is integrally united to the coupler head.

Mounted within the coupler head is a slidable locking block 5 which assumes locked position under the influence of gravity. The lock 5 is vertically movable within the head and normally extends into the path of movement of the tail of the knuckle so as to lock said knuckle in coupled position.

The lock is moved to unlocked position by means of a lifter with which it is slidably and rotatably associated. In the present instance the lifter 6 is of the bottom operating type extending downwardly through an opening in the coupler head 1 and pivotally connected at its lower end to a suitable operating lever 7 which may advantageously be formed as a bell crank pivoted to the guard arm side of the coupler head at 8. In order to form the sliding and pivotal connection of the lifter 6 and lock 5, it is preferred to provide the upper end of the lifter with oppositely disposed trunnions 9 which pro-

ject into trunnion guideways 10 of the locking block, the latter being fashioned with an upwardly and rearwardly opening slot 11 for receiving the lifter.

5 The lifter 6 cooperates with the coupler head to prevent the locking block 5 from accidentally moving to unlocked position when the coupler is in service. For the purpose of performing this function the rear side of 10 the lock lifter is formed with an upwardly facing inclined shoulder 12 which is adapted to extend under a cooperating lock-down shoulder or lug 13 of the coupler head when the locking block is in locked position. As 15 will be apparent from Figs. 2 and 4, if the lock 5 should accidentally be jarred upward toward unlocked position the lifter 6 will be drawn upwardly by the lock until its shoulder 12 engages the stop shoulder 13 of the 20 coupler head, thus arresting the accidental unlocking movement of the lock. When the lock lifter is actuated by the uncoupling lever 7 to effect an unlocking movement of the lock, the lifter first moves vertically with 25 respect to the lock 5 until its inclined shoulder 12 engages the cooperating shoulder 13 of the coupler head. After the inclined faces 12 and 13 have thus been brought into contact, continued upward pressure upon the 30 lifter forces its upper end to be retracted into the lock, thus causing the shoulder 12 of the lifter to escape from beneath the lock-down lug 13 and thereby, as shown in Fig. 5, releasing the lock so that it may execute 35 an unlocking movement. To cause the lifter 6 to move vertically during its initial unlocking movement, said lifter is preferably provided with a vertically extending face 14 which engages the adjacent vertical face of 40 the lock 5 when the parts are in locked relation; and said lifter is also preferably fashioned with a rearwardly facing vertical surface 15 adapted to bear against the forward face 16 of the lock down lug 13. By respectively cooperating with the locking block 45 and the coupler head these faces 14 and 15 of the lifter constrain the lifter to move vertically until the shoulders 12 and 13 come into operative contact. For a similar purpose it is also preferred to provide the 50 lower faces of the trunnion guides of the locking block with vertically extending shoulders 17 which cooperate with the respectively adjacent trunnions 9. In addition to guiding the lifter vertically during 55 its initial unlocking operation, the vertical faces or shoulders 14 and 15 serve to prevent the lifter from accidentally rotating in a direction which would cause its locking shoulder 12 to swing or move from beneath the cooperating lock-down shoulder 13 when the coupler is in service.

60 After the lifter has been guided into the lock so as to assume the position shown in Fig. 5, its further upward movement raises

the locking block to unlocked position as shown in Figs. 6 and 7 or, if the unlocking movement is extended, then to the position shown in Fig. 8 which corresponds to the final position of the parts when the knuckle 70 has been rotated to open position by means of the knuckle opener lever. To enable the lock 5 to be supported in lock-set position so as to permit the knuckle to open, the locking block is formed with a downwardly projecting lock-set leg 18 whose lower end is adapted to rest upon a lock-set ledge or seat 19 on the upper surface of the tail of the knuckle 2. The ledge 19 extends part way along the rear edge of the tail of the knuckle and gradually narrows, so that as the knuckle 2 performs an uncoupling rotation the lock-set projection 18 rides off the knuckle, thus allowing the lock to drop until the under surface of its knuckle locking portion rests upon the upper surface of the knuckle tail. When the knuckle subsequently rotates inwardly to coupled position its tail passes from beneath the locking block 5 and the latter then drops to locked position.

80 In assuming lock-set position the locking block 5 tilts forwardly. While the upper ends of the trunnion guideways 10 are located above and in advance of the center of gravity of the lock 5 so that its weight acts to induce the tilting movement, means are provided whereby such tilting movement is positively effected. To this end the short arm 20 of the knuckle opener 21 is formed with a rearwardly projecting lug or extension 22 with which the locking block engages when the latter (see Fig. 6) has been raised high enough for its lock-set leg 18 to clear the lock-set seat 19 of the knuckle tail. To cooperate with the extension 22 of the knuckle opener the upper end of the locking block 5 is formed adjacent the tail of the knuckle with a forwardly and downwardly inclined surface or shoulder 23. Where car conditions make it necessary to limit the vertical height of the coupler this sloping surface 23 is, as shown, preferably located below the top of the locking block. As shown in Fig. 6, the extreme rearward end of the projection 22 of the knuckle opener contacts the inclined surface 23 on the locking block at a point to the rear of the center of the lifter trunnions 9, and continued upward movement of the lifter therefore results in positively tilting the locking block to lock-set position, as shown in Fig. 7. To permit the lock 5 to tilt to lock-set position after having been sufficiently raised, the upper portion 24 of the rear face of the lock is beveled or inclined, and for a similar purpose the lower portion of the forward face of the lock is inclined as at 25. As the lock-set leg 18 projects laterally from the body 85 of the locking block and overlaps the inner 90

end of the tail of the knuckle 2 when the parts are in locked relation, it serves to prevent the lock from tilting forwardly until after the lock 5 has assumed a position permitting the knuckle to open.

The tilting of the lock 5 during its unlocking movement causes the knuckle opener actuating shoulder 26 thereof to engage the shorter arm 20 of the knuckle opener, as shown in Figs. 7 and 8. As the rearward extension 22 of the knuckle opener is at that time in contact with the inclined surface 23 of the lock at a point to the rear of the lifter trunnions 9, and as the shoulder 26 of the locking block is in advance of said trunnions, the contact points of the locking block with the knuckle opener are established on opposite sides of the center of the lifter trunnions 9, thereby causing the lock 5 to be maintained in a tilted position during the extended unlocking movement necessary to effect a knuckle throwing rotation of the knuckle opener upon its pivot pin 27. This tilting of the locking block is effective in causing an extended rotation of the knuckle opener without undue vertical movement of the lock. Instead of forming the knuckle opener actuating shoulder 26 as the upper surface of a lug or projection carried by the locking block, it is advantageous to form it as the base of a recess 28 with which the locking block 5 is provided on the forward side adjacent the tail of the knuckle. This recess receives the short arm 20 of the knuckle opener when the lock is in tilted position. By this means ample bearing area between the lock and the tail of the knuckle is secured in a coupler of very limited vertical dimension.

The pivot pin 27 for the knuckle opener may advantageously be cast in place in the coupler head 1; and the pivot pin 3 of the movable knuckle is preferably removable downwardly, having a head at its lower end and being supported in assembled position by means of a sustaining pin 29 passing through suitable perforated lugs with which the coupler may be provided on its underside.

We claim:

1. A car coupler involving a coupler head, a knuckle pivotally mounted on the head, a gravity actuated lock for the knuckle, and a lifter for operating said lock, said lock and lifter being adapted to have relative sliding and swinging movements, said head having a shoulder for cooperating with the lifter to prevent accidental unlocking of the lock, said lifter being formed with a shoulder adapted to engage the shoulder of the coupler head, one of said shoulders extending at an angle to the direction of unlocking movement of the lock, said shoulders being adapted upon a normal unlocking

movement of the lifter to cooperate so as to force the shoulder upon said lifter from beneath said shoulder of the coupler head, and said lock when moved to unlocked position by the lifter being adapted to be tilted upon said lifter so as to be supported in unlocked position on the tail of said knuckle while the latter is in closed position.

2. A car coupler involving a coupler head, a knuckle rotatably mounted on the head, a lock for the knuckle, a rotatable knuckle opener lever for moving the knuckle to open position, and a lifter for actuating the lock, said lifter being slidably and rotatably connected to said lock, said lock being adapted to move into engagement with said knuckle opener lever and to be thereby forced to rotate with respect to said lifter so as to assume a tilted position permitting it to be supported in unlocked position on the tail of the knuckle while the latter is closed.

3. A car coupler involving a coupler head, a knuckle rotatably mounted on the head, a lock for the knuckle, a rotatable knuckle opener lever adapted to be actuated by the lock to force the knuckle to open position, and a lifter for actuating the lock, said lock being movable with respect to said lifter and being adapted to be tilted by engaging said knuckle opener and to actuate the knuckle opener when in the tilted position.

4. A car coupler involving a coupler head, a knuckle rotatably mounted on the head, a rotatable knuckle opener lever for moving the knuckle to open position, a lock for the knuckle adapted to actuate said lever, and means for causing the lock to perform an unlocking movement, said knuckle opener lever being provided with a rearwardly extending portion adapted to cooperate with said lock to cause the latter to assume a tilted position permitting it to be supported in unlocked position while said knuckle is closed.

5. A car coupler involving a coupler head, a knuckle rotatably mounted on the head, a lock for the knuckle, a rotatable knuckle opener lever for forcing the knuckle to open position, and means for causing the lock to perform an unlocking movement, said knuckle opener lever having an arm adapted to be engaged by the lock and being provided with a projection extending rearwardly from said arm, and said lock being formed with a recess adapted to receive said arm and having an inclined face adapted to engage said projection, said lock when in unlocked position being adapted to assume a tilted position permitting it to be supported in unlocked position while the knuckle is closed.

6. A car coupler involving a coupler head, a knuckle rotatably mounted on the head, a lock for the knuckle, a rotatable knuckle

opener lever adapted to be actuated by the lock to force the knuckle to open position, and a lifter for actuating the lock, said lifter being provided with trunnions upon which the lock is adapted to rotate, and said lock when rotated on said trunnions being adapted to contact said knuckle opener at

points on opposite sides of the axis of said trunnions.

In testimony whereof we affix our sig- 10 natures.

WILLIAM J. REGAN.
WILLIAM KELSO.
